(75) Inventors: **Stephen W. Hoxie; André Akers**, both of San Antonio, TX (US)

* cited by examiner

(73) Assignee: **The United States of America as represented by the Secretary of the Army**, Washington, DC (US)

(**) Term: **14 Years**

(21) Appl. No.: **29/127,226**

Primary Examiner—M. H. Tung

(74) Attorney, Agent, or Firm—Elizabeth Arwine

(22) Filed: **Aug. 3, 2000**

(57) **CLAIM**

The ornamental design for an icon for a portion of a display screen, as shown and described.

(51) LOC (7) Cl. **14-02**

DESCRIPTION

(52) U.S. Cl. **D14/492**

(58) Field of Search D14/485-495; D18/24-33; D19/6; D20/11; D21/324-33; 345/326, 339-58

The single FIGURE is a front view of a icon for a portion of a display screen. The broken line drawing of a portion of a display screen is for illustrative purposes only and forms no part of the claimed design.
